UNITED STATES PATENT OFFICE.

GRACE MARY QUACKENBUSH, OF NEW YORK, N. Y.

DESIGN FOR A POST FOR CHILDREN'S TOYS, FURNITURE, AND FENCES.

48,043.

Specification for Design.

Patented Oct. 26, 1915.

Application filed April 7, 1915. Serial No. 19,813. Term of patent 14 years.

To all whom it may concern:

Be it known that I, GRACE MARY QUACKENBUSH, a citizen of the United States, residing at No. 31 West Sixty-eighth street, in the city and county of New York and State of New York, have invented a new, original, and ornamental Design for Posts for Children's Toys, Furniture, and Fences, of which the following is a specification, reference being had to the accompanying drawing, forming part thereof.

The figure is an elevation of a post, showing my new design.

Copies of this patent may be obtained for five cents each, by addressing the "Commissioner of Patents, Washington, D. C."

I claim:

The ornamental design for a post for children's toys, furniture, and fences, as shown.

In testimony whereof I affix my signature in presence of two witnesses.

GRACE MARY QUACKENBUSH.
